UNITED STATES PATENT OFFICE.

EMANUEL W. BLOOMINGDALE, OF NEW YORK, N. Y.

DESIGN FOR A BOTTLE.

SPECIFICATION forming part of Design No. 18,718, dated November 6, 1888.

Application filed September 10, 1888. Serial No. 285,078. Term of patent 3½ years.

To all whom it may concern:

Be it known that I, EMANUEL W. BLOOMINGDALE, a citizen of the United States, and a resident of New York, in the county of New York and State of New York, have invented and produced a certain new and original Design for Bottles, of which the following is a specification, reference being had therein to the accompanying drawing, which shows a side elevation, partly in section, of a bottle having the general shape of a revolver.

The leading feature of my design consists in a recess part way around the bottle at the point where in a revolver the chambers are placed.

The barrel *b* is shown as interiorly tapered

at *d* and provided with a cork or stopper, *c*, and at *a* is represented a recess in place of the usual ammunition-chamber in a fire-arm, which recess extends around the bottle, except at the point where the handle-stock extends. 20

What I claim is—

The design for a bottle having the shape substantially as herein shown and described.

Signed at New York, in the county of New York and State of New York, this 31st day of 25 August, A. D. 1888.

E. W. BLOOMINGDALE.

Witnesses:

ARTHUR S. LEVY,

C. C. GARRISON.
